UNITED STATES PATENT OFFICE

WALTER M. CHARMAN AND HARRY J. DARLINGTON, OF YOUNGSTOWN, OHIO; SAID DARLINGTON ASSIGNOR TO SAID CHARMAN

MOLD WIPER FOR HOT TOPS

Application filed February 24, 1930. Serial No. 430,663.

This invention relates to hot tops, that is removable tops for ingot molds, such tops having the capacity of insulating the upper part of the ingot so as to delay the dissipation 5 of heat, thereby maintaining for a time a mass of molten metal at the top of the ingot which descends to fill the cavities in the center of the ingot produced by the shrinkage of metal as the ingot cools. The present invention relates 10 particularly to a hot top comprising a metal casing with a non-burning or slow-burning sheet, lining the inner walls of the hot top and the bottom edge of the casing and extending outwardly to the wall of the mold, and adapted to wipe the same as the hot top is lowered into the mold.

One of the objects of the invention is the provision of a mold wiper mounted upon the hot top near the bottom thereof and adapted 20 to contact the mold wall so as to prevent hot metal from flowing upwardly into the annular space between the hot top and the mold wall when the hot top is lowered into the mold.

Another object is the provision of means 25 for protecting the lower end of the casing from the hot metal of the ingot, this being effected preferably by the same sheet material that is employed for the mold wiping function.

30 A further object is the provision of means for supporting this combination lining and wiping strip upon the casing in such manner that the said means is adapted to fail when the hot top is stripped from the ingot, this strip thus constituting a parting strip between the 35 ingot and the hot top, and being left behind when the hot top is stripped from the ingot.

Other objects and features of novelty will appear as we proceed with the description of 40 those embodiments of the invention which, for the purposes of the present application, we have illustrated in the accompanying drawing, in which

45 Figure 1 is an elevational view of a substantially rectangular hot top embodying the invention.

50 Figs. 2 to 9 inclusive are fragmental vertical sectional views showing various modifications of wiper strips in operative relation with the mold wall.

Fig. 10 is a top plan view of one section of the wiper strip illustrated in Fig. 8 as applied to use upon a hot top of the general form of Fig. 1.

Fig. 11 is a cross section on the line 11—11 55 of Fig. 10.

Fig. 12 is a plan view of a similar wiper strip adapted for use upon a hot top designed for a fluted circular mold, and

Fig. 13 is a cross section upon the line 60 13—13 of Fig. 12.

In Fig. 1 we have illustrated a metal casing composed of two members 10, each of which includes a side and the adjacent corners of the casing, and two members 11 which are interposed between the members 10 on opposite sides of the casing. The members 10 and 11 are provided along the upper portions of their contacting edges with flanges or lugs 12 for the reception of bolts 13 or the like, by means of which the members of the casing are fastened securely together. The flanges 12 extend only part way down the sides of the casing, and hence the lower portion of the casing is left smooth and of regular contour 75 in order that it may enter the top of the mold. On opposite sides of the casing we provide trunnions 14 for convenience in handling.

The interior construction of this form of 80 the invention is illustrated in Fig. 8. By reference to that figure it will be noted that the casing is provided at its lower edge with an inwardly extending ledge 15. This ledge extends throughout the inner perimeter of 85 the casing, and supports the upper lining members 16, which are preferably formed of refractory material and so interfitted as to be held in place with or without cement. A small air space 17 between the casing and the 90 lining may be provided for insulation purposes, if desired. In order to separate the lower surface and the inner edge of the ledge 15 from the molten metal, we provide a lower lining course made up of blocks 18 which are 95 recessed to receive the ledge 15. The blocks 18 therefore meet the lower edge surfaces of lining members 16. The blocks 18 are retained upon the casing 11 by some fastening means which is adapted to fail when the hot 100

top is stripped from the ingot. For this purpose we have shown in the present instance a wire 19 passed through holes 20 and 21 in the casing and block 18, bent down along the outer side of the hot top, and the ends twisted together beneath the block 18. Further details of this lower block arrangement are disclosed in our copending application Ser. No. 417,326, filed December 30, 1929.

10 The casing 10, 11 is provided along its outer lower edge with a shallow rabbet 22 of size sufficient to receive a sheet metal wiper strip 23, illustrated in plan and section in Figs. 10 and 11 respectively. This strip is 15 conveniently made in four parts in the case of a rectangular hot top. The outer edge of the strip 23 extends far enough away from the casing of the hot top to engage with the mold wall 24 when the hot top is lowered 20 into the mold, and in order that the greatest advantage may be taken of the flexibility of the strip, it is preferably deflected upwardly, as shown in Figs. 8 and 11. At the point where the wire 19 intersects the strip 23, 25 the latter may be cut away as indicated at 25 in Fig. 10. The wall 24 of the mold is ordinarily tapered downwardly so that the inner diameter engaged by the strip 23 varies with the extent that the hot top is lowered 30 into the mold. For practical reasons it is highly desirable to be able to vary this extent within certain limits. The sheet material of which the strip 23 is formed, having flexibility, is able to conform with the 35 mold wall and make a tight joint for all of the height adjustments of the hot top.

In the use of this form of the invention, after the lining 16 has been coated with a suitable facing compound in order to effect 40 satisfactory parting, the hot top is caused to enter the mold a predetermined distance, and is then temporarily supported upon the mold in a manner well known in the art. The hot metal is poured through the hot top until it fills the mold and rises to a predetermined height within the hot top. In the course of this pouring the metal flows into the narrow space around the hot top below the wiper strip 23, such flow being limited 45 by the strip. This thin annular lip or fin of metal quite quickly congeals or "freezes", and then itself acts to assist in stopping further flow. Furthermore, the metal wiper strip, being in contact with the hot top casing and preferably with the mold wall as well, conducts away rapidly heat transmitted to it from the molten metal, and thus acts to chill the metal directly adjacent thereto. 50 After the ingot is cooled sufficiently, the operator causes the trunnions 14 to be grasped by suitable hoisting mechanism and strips the hot top away from the ingot. The blocks 18 tend to cling to the ingot, and this adherence being much stronger than the wires

19, the latter break and pull out of the holes 20 in the casing, leaving the blocks 18 upon the ingot. Of course it will be understood that the blocks 18 making up the lower course of lining material are intended to be used but once, but inasmuch as these blocks are comparatively small, and inasmuch as the lining members 16 are semi-permanent, the expense per ingot is low.

In Figs. 12 and 13 we have illustrated a wiper strip 26 of a character similar to that just described, but intended for use upon a round hot top that is employed in connection with a round mold having fluted internal walls. The curved projections 27 of the strip 26 are shaped to conform with and extend into the flutes of the mold. In the case of a hot top of this shape, it is convenient to form the strip 26 in three sections.

In the form of the invention illustrated in Fig. 2, the metal casing 28 is provided with an inner ledge 29 spaced from the bottom of the casing and supporting a lining course 30 of refractory or other suitable material. Below this course we mount, by means of pins 31 which are adapted to fail upon the application of heat from the molten metal, a combined lower lining and wiper strip 32 of sheet material, for example sheet metal. This material has an outturned flange 32' at its upper edge which contacts with the lower edge surface of the lining course 30. When the hot top is stripped from the ingot the strip 32 remains thereupon, and of course a new strip must be mounted upon the hot top before it is again used.

In Fig. 3 we have shown a casing 33 having a lower ledge 34 which is curved on its lower and inner sides. Non-burning or extremely slow-burning sheet material 35 extends around the curved surface of the ledge 34 and upwardly along the inner wall of the hot top to the upper edge of the latter where it is provided with tabs 36 which may be bent over against the upper edge of the hot top to hold this sheet material in place. Sheet metal is the material which we prefer to employ. We may interpose refractory or other insulating material 37 between the casing 33 and the sheet material 35, although this is not essential in the broader aspects of the invention. When the hot top is stripped from the ingot the entire sheet 35 adheres to the ingot, the lifting force applied to the hot top causing the tabs 36 to be bent upwardly out of the way. In this case the sheet 35 serves as a temporary inner and lower lining member, as well as a wiper strip, and this double function is present in the case of several of the modifications later to be described.

In the form of the invention shown in Fig. 4, the metal casing 38 has an internal ledge 39 which is protected by a temporary combined lining member and wiper strip 40, provided with tabs 41 which are adapted to pull out

or break off when the hot top is stripped from the ingot. While, in this construction, it would be in order to employ refractory upper lining members, similar to those illustrated in Figs. 2 and 3, we prefer to employ a sleeve 42 of metal or other non-burning or slow-burning material, spaced a considerable distance from the casing wall, and to fill the space intervening with loose insulating material 43. When metal is employed for the sleeve 42, it is preferably a hardened casting, and the surface which contacts with the molten steel may be impregnated with chromium or other substance tending to insure a smooth hard surface.

In Fig. 5 the casing 44 is a metal member, to the bottom of which is secured a separable and renewable ledge 45. This ledge may be supported by means of dowel pins 46 that extend through smooth holes in the casing 44 and are threaded into tapped openings in the ledge 45. On this ledge the upper lining 47 may be supported. In order to form a parting surface, the ledge 45 is coated on its inner and lower sides with a facing compound 48 of suitable character. Then a combined parting strip and wiper strip 49 of sheet material is secured to the ledge by means of nails 50 driven through the strip into blocks 51 of wood or the like that are set into spaced sockets formed in the ledge. When the hot top is stripped from the ingot, the nails 50 pull out of the blocks 51, and the strip 49 is left upon the ingot. Before each casting operation new blocks 51 are fitted into the sockets, a new coating 48 is applied to the ledge, and a new strip 49 is nailed onto the ledge.

In Fig. 6 a casing 52 is employed having a ledge 53 which is provided with a rabbet at its upper inner corner for the reception of a flange or tabs 54 on a combined lining and wiper strip sheet 55. Upper lining members 56 rest upon the ledge 53 and upon the flange 54. The sheet 55 remains with the ingot when the hot top is stripped therefrom, the tabs or flange 54 being broken off in the process. Their connection with the main portion of the sheet 55 may of course be weakened so as to facilitate such breaking, or the separation of the sheet 55 from the hot top may be effected by merely pulling the tabs or flange 54 out of the rabbet in the ledge.

In Fig. 7 the casing 57 has a ledge 58 formed integral therewith, adapted to support the inner lining member 59 of refractory material, this member having a depending portion 60 which covers the inner face of the ledge 58. Plugs or blocks of wood 61 are set into the ledge 58, as in the case of the construction shown in Fig. 5, and to these blocks are secured by nails 62 a lining and mold wiping strip 63, the latter covering not only the ledge 58, but also the lower ends of the lining elements 59. The strip 63 breaks

away from the hot top when it is stripped from the mold in the same manner as above described in connection with Fig. 5.

The modification of Fig. 9 comprises a casing 64 with a ledge 65 extending inwardly therefrom at a short distance above the bottom of the casing. This ledge supports the upper lining members 66. Refractory blocks 67 of irregular shape are secured to the casing 64 by removable pins 68 which are threaded into the casing. A combined lower lining and wiper strip 69, similar to the strip 32 of Fig. 2, is then applied and held in place by tabs 70 which extend between the blocks 66 and 67. These tabs break away or pull out when the hot top is stripped from the mold, and the sheet 69 is left behind.

The forms of the invention illustrated in Figs. 2 and 3 are the same as disclosures in our copending application, Serial No. 85329,486, filed December 31, 1928, and as to those forms, as well as to the use of a wiper strip broadly, the present application is a continuation in part of that application.

While in the foregoing description and in the accompanying drawing we have disclosed certain embodiments of the invention more or less in detail, we desire it to be understood that such detail disclosures have been resorted to primarily for the purpose of fully illustrating the invention as required by the statute, and are not to be construed as amounting to limitations upon the scope thereof.

Having thus described our invention, we claim:

1. In a hot top for ingot molds, sheet material mounted on the hot top protruding outwardly therefrom near the bottom thereof, said material being shaped at its outer edge to conform with and wipe the mold wall as the hot top is lowered into the mold.

2. In a hot top for ingot molds, flexible sheet material mounted on the hot top and protruding outwardly therefrom near the bottom thereof to wipe the mold wall as the hot top is lowered into the mold.

3. In a hot top for ingot molds, a wiper strip mounted on the hot top and protruding outwardly therefrom throughout its perimeter, said strip being adapted to contact with and wipe the mold wall as the hot top is lowered into the mold.

4. In a hot top for ingot molds, a flexible metal strip mounted on the hot top and protruding outwardly therefrom near the bottom thereof to wipe the mold as the hot top is lowered thereinto.

5. In a hot top for ingot molds, a flexible metal strip mounted on the hot top and protruding outwardly therefrom near the bottom thereof, said strip being deflected upwardly near its outer edge, whereby it is adapted to wipe the mold wall as the hot top is lowered into the mold.

6. A hot top for ingot molds adapted to extend downwardly into the mold, comprising a metallic casing, and a heat resisting flexible material extending over the bottom of the casing and upwardly along the inner side thereof. 70
7. A hot top for ingot molds adapted to extend downwardly into the mold, comprising a metallic casing, a heat resisting flexible material extending over the bottom of the casing and upwardly along the inner side thereof, and means for retaining said material upon the hot top, said means being adapted to fail when the hot top is stripped from the ingot. 75
8. A hot top for ingot molds adapted to extend downwardly into the mold, comprising a metallic casing, and a heat resisting flexible material extending over the bottom of the casing and upwardly along the inner side thereof, said material protruding outwardly beyond the outer wall of the hot top to wipe against the mold wall when the hot top is lowered into the mold. 80
9. A hot top for ingot molds adapted to be supported upon the ingot, comprising a metallic casing, and a sheet metal lining extending over the bottom of the casing and upwardly along the inner side thereof. 90
10. A hot top for ingot molds adapted to be supported upon the ingot, comprising a metallic casing, and a sheet metal lining extending over the bottom of the casing and upwardly along the inner side thereof, said lining being adapted to contact with the inner wall of the mold. 95
11. In a hot top for ingot molds adapted to extend downwardly into the mold, a casing, heat resisting sheet material mounted upon the hot top beneath the casing, and means for supporting said material, said means being adapted to fail when the hot top is stripped from the ingot. 100
12. In a hot top for ingot molds adapted to extend downwardly into the mold, a casing, heat resisting sheet material mounted upon the hot top extending outwardly beneath the casing and adapted to contact with the inner wall of the mold, and means for supporting said material, said means being adapted to fail when the hot top is stripped from the ingot. 110
13. In a hot top for ingot molds adapted to extend downwardly into the mold, a metal casing having an internal ledge near the bottom thereof, a lining for the casing supported upon said ledge, heat resisting sheet material extending along the bottom surface of said ledge, and means for supporting said material from said casing, said means being adapted to fail when the hot top is stripped from the ingot. 120
14. In a hot top for ingot molds adapted to extend downwardly into the mold, a metal casing having an internal ledge near the bot- 125
- tom thereof, a lining for the casing supported upon said ledge, heat resisting sheet material extending along the bottom surface of said ledge and outwardly therefrom to contact with the inner wall of the mold when the hot top is lowered into the mold, and means for supporting said material from said casing, said means being adapted to fail when the hot top is stripped from the ingot. 130
15. In a hot top for ingot molds adapted to extend downwardly into the mold, a metal casing having an internal ledge near the bottom thereof, a lining for the casing supported upon said ledge, and sheet material extending over the inner edge of said ledge and outwardly along the bottom surface of the ledge and beyond the casing. 85
16. In a hot top for ingot molds adapted to extend downwardly into the mold, a metal casing having an internal ledge near the bottom thereof, a lining for the casing supported upon said ledge, sheet material extending over the inner edge of said ledge and outwardly along the bottom surface of the ledge and beyond the casing a distance sufficient to enable said material to wipe the wall of the mold as the hot top is lowered thereinto, and means for supporting said material from said casing, said means being adapted to fail when the hot top is stripped from the ingot. 90
17. In a hot top for ingot molds adapted to extend downwardly into the mold, a metal casing having an internal ledge near the bottom thereof, a lining for the casing supported upon said ledge, non-burning sheet material extending from the top of the hot top downwardly over the inner wall thereof and the inner edge of said ledge and outwardly along the lower surface of said ledge, and means for supporting said material, said means being adapted to fail when the hot top is stripped from the ingot. 100
18. In a hot top for ingot molds adapted to extend downwardly into the mold, a metal casing having an internal ledge near the bottom thereof, a lining for the casing supported upon said ledge, and non-burning sheet material extending from the top of the hot top downwardly over the inner wall thereof and the inner edge of said ledge and outwardly along the lower surface of said ledge beyond the casing a distance sufficient to enable said material to wipe the wall of the mold as the hot top is lowered thereinto. 110
19. In a hot top for ingot molds, a casing, a course of lining material supported from said casing and protecting the lower edge thereof, and a flexible wiper strip mounted on the hot top between the casing and the said lining material, one of said last named elements having a recess therein for the reception of the said wiper strip. 120
20. In a hot top adapted to extend downwardly into an ingot mold, a preformed material shaped at its outer edge to conform 130

- with the inner wall of the mold, mounted on the hot top to protrude outwardly therefrom, and adapted to dam the upward flow of metal around the exterior of the hot top.
- 5 21. In a hot top for ingot molds, material mounted on the hot top protruding outwardly therefrom near the bottom thereof, said material being shaped at its outer edge to conform with the inner surface of the mold 10 wall, and being adapted to chill the molten metal adjacent thereto.
22. In a hot top for ingot molds, a metal casing, heat conducting material in contact with said casing extending outwardly therefrom near the bottom thereof, said material being adapted to span the space between the hot top and the inner wall of the mold and to act as a chill for congealing the molten metal adjacent thereto.
- 20 23. In a hot top adapted to extend downwardly into an ingot mold, means for temporarily supporting the hot top during the pouring of the ingot, and means carried by the hot top above the lower end thereof 25 adapted to assist in the chilling of that portion of the ingot lying between the hot top and the mold wall.

In testimony whereof, we hereunto affix our signatures.

CERTIFICATE OF CORRECTION.

Patent No. 1,804,207.

Granted May 5, 1931, to

WALTER M. CHARMAN ET AL.

It is hereby certified that error appears in the above numbered patent requiring correction as follows:
In the drawing, Figure 8, should appear as shown below instead of as shown in the drawing;

and that the said Letters Patent should be read with this correction therein that the same may conform to the record of the case in the Patent Office.

Signed and sealed this 8th day of September, A. D. 1931.

(Seal)

M. J. Moore,
Acting Commissioner of Patents.
